UNITED STATES PATENT OFFICE

LEO L. RICHARDSON, OF CLEVELAND, OHIO, ASSIGNOR TO THE CLEVELAND ROCK DRILL COMPANY, OF CLEVELAND, OHIO

HOLE CLEANER

Application filed October 24, 1928. Serial No. 314,780.

The present invention is directed to improvements in hole cleaners for use in connection with percussive drills.

The primary object of the invention is to provide a device of this character constructed and arranged in such manner that the fluid controlling valve can be held in a position to permit pressure fluid under line pressure to pass through the drill and drill steel to blow the cuttings from the drill hole.

Another object of the invention is to provide a device of this character which is simple in construction, and which can be conveniently controlled by the drill runner.

The above and other objects and advantages of my improvement will fully appear from the following description with the accompanying drawings and be explicitly defined in the appended claims. It will be understood, however, that this disclosure is illustrative only, and that the principle of the invention can be embodied in construction other than the one specified herein.

In the accompanying drawings:—

Figure 1 is a sectional diagrammatic view showing the parts in their normal working position.

Figure 2 is a similar view, showing the position of the parts during the blowing operation.

Referring to the drawings, 1 designates the cylinder in which is reciprocable the piston hammer 2 having a fluted extension 2' for rotating the chuck 3, and thus the drill steel 4 therein, rotary movement being imparted to the hammer by the rifle bar 5 and ratchet mechanism 6. The construction thus described is conventional, and no claim is made therefore specifically.

Associated with the cylinder is a valve chest 7 in which is provided a chamber 8, said chamber having fitted in its ends plugs 9 and 10, the latter having a stem 11 which extends to and through the plug 9 and upon this stem 45 is slidable the sleeve 12 of the valve 13. The valve 13 includes a central flange 14 and spaced terminal flanges 15. Surrounding the plugs 9 and 10 are end chambers 16 and 17, respectively, the former opening to atmosphere through the duct 18. Motive fluid is

introduced to the valve chamber 8 through the supply port 19 which opens into annular groove 20, there being upon opposite sides of this groove annular channels 21 and 22, which have communicating therewith, respectively, the main fluid distributing passages 23 and 24, which open into the front and rear ends of the hammer chamber 25, respectively.

The walls of the chamber 8 has formed therein annular exhaust channels 26 which are open to atmosphere through the ports 27. The end chambers 16 and 17 are in communication with the hammer chamber 25 through the crossed "kick off" ports 28 and 29, respectively.

The sleeve of the valve 13 is formed upon opposite sides of the flange 14 with comparatively small orifices 30 and 30', which afford communication between the passages 23 and 24 and the pressure and relief chambers 31 and 32 defined by the inner ends of the plugs 9 and 10 and adjacent ends of the sleeve 12. The construction and operation of the valve is the same as that disclosed in the patent to Gustave M. Nell, issued October 19, 1926, No. 1,603,705.

The plug 10 has formed therein an axial counter-bored socket 32', the inner end of which communicates with the chamber 32 through an angular passage 33.

A valve 34 is employed and includes a shank 35 for rotatable engagement in the socket 32', said shank having a handle 36 carried thereby, and associated therewith is a spring pressed latch 37 operating to hold the handle and thus the shank in selected positions. The shank has formed in its inner end relatively short angularly disposed communicating ports 38 and 39, and a diagonally disposed passage 40, which when in the position as shown in Figure 1 places the duct 41 and port 42 in communication in order that residue air in the chamber 17 can pass therefrom to atmosphere, as it does through the duct 18, upon reversal of the valve 13. Leading from the socket 32'' is a passage 43 which opens into the chamber 17, said passage being adapted to be brought into registration with the port 39, the purpose of which will be later explained.

Briefly the operation is as follows:

The passage 40 is in communication with the duct 41 and port 42 in order that the residue air will exhaust from the chamber 17, and when the parts are in this position the valve 13 is free to reciprocate, under the action of motive fluid admitted alternately into end chambers 16 and 17 from the cylinder by way of the crossed "kick off" ports 28 and 29 respectively, to control the distribution of pressure fluid to the hammer chamber to actuate the piston hammer, and in the same manner as disclosed in the patent referred to. After a period of drilling it is found desirable to blow the cuttings from the hole, the valve 34 is rotated a quarter turn, thus rotating the shank 35 thereof, whereupon the passage 40 is moved out of registration with the duct 41 and port 42 to permit the escape of air from the chamber 17, and at which time the piston hammer closes the passage 29 to prevent leakage of air from the chamber 17. Live air from the supply port 19 will enter the orifice 30' into the chamber 32 and acts upon one end of the sleeve 12. The chamber 17 will be supplied with live air from chamber 32 through passage 33, ports 38 and 39, and passage 43. The live air in the chambers 32 and 17 will overcome the pressure of the live air reaching chamber 16 through the port 28, thereby holding the valve in the position shown in Figure 2. The major quantity of air from the line will enter the chamber 25 through the passage 24 driving the piston forwardly and from thence past the rifle bar 5, through the bore 44 of the hammer extension into the bore 45 of the drill steel. The air flowing thus, under line pressure will obviously blow the cutting from the hole being drilled. After the hole has been blown, the valve 34 and its shank are turned reversely in order that the parts will again be positioned to permit free movement of the valve and reciprocation of the piston hammer.

What is claimed is:

The combination with a cylinder having a piston hammer reciprocable therein, of a valve chest communicating with a source of motive fluid, a stem in the chest, a valve slideable on the stem for effecting the supply and exhaust of the motive fluid to and from the cylinder, said chest having chambers at the opposite ends of said valve communicating with the opposite ends of said cylinder to effect reciprocation of said valve, a valve shank rotatably associated with said stem, said valve shank and said stem having co-operating ports arranged in one position of said valve shank to conduct motive fluid through the stem to one of said chambers to act against the end of the valve and hold the same inactive.

In testimony whereof I affix my signature.
LED L. RICHARDSON.
